UNITED STATES PATENT OFFICE.

PIETER GERRIT VAN WIJK, OF GELDERMALSEN, NETHERLANDS.

OVERLOAD SWITCH OR CUT-OUT.

1,280,594.

Specification of Letters Patent.

Patented Oct. 1, 1918.

Application filed May 23, 1916. Serial No. 99,357.

To all whom it may concern:

Be it known that I, PIETER GERRIT VAN WIJK, subject of the Queen of the Netherlands, residing at Geldermalsen, Kingdom 5 of the Netherlands, have invented certain new and useful Improvements in or Relating to Overload Switches or Cut-Outs, of which the following is a specification.

This invention relates to automatic over-10 load switches having a delayed or retarded action. The object of the invention is to provide a switch of this kind of simple construction and sufficient reliability of action, and in which the duration of the delay can 15 be regulated in a simple manner.

According to this invention, the part which normally holds the switch locked, is held in contact with the circumference of a disk rotatable about a fixed spindle, by 20 springs or by a weight. The said disk is provided in its circumference with a recess into which the locking bar can be forced by spring pressure or by the action of a weight, when the disk is turned to such an extent 25 that the recess is brought opposite the locking bar. The turning of the disk is effected by the attraction of an iron core by a coil. The rotation of the disk is retarded owing to its spindle driving, by means of a speed-30 multiplying gear, an auxiliary spindle which drives one or more rollers or sliding parts which, during their rotation about the said spindle, are pressed, in opposition to the action of springs, by centrifugal force 35 with adjustable tension against the inner circumference of a fixed hollow cylinder, the axis of which coincides with the axis of rotation of the said rollers.

A construction according to this invention 40 is illustrated by way of example in the accompanying drawing in which—

Figure 1 is a side elevation of the release, Fig. 2 a front elevation,

Fig. 3 a side elevation of that part of the 45 apparatus which brings about the retardation or delay, and

Fig. 4 is a front elevation of the parts shown in Fig. 3.

The knife contacts 1 of the switch are 50 locked by a locking pawl 2 which can be disengaged by means of the unlocking bar 3. The knife contacts are then lifted in the known manner by the action of the weight 4, out of the spring contacts 5, and the lever 6 to which the weight is secured, strikes against a fixed stop. The unlocking bar 3

is raised by a spring 8 and on its upper end is a roller 9, for the purpose of reducing the friction, which engages with the circumference of a disk 10 rotatable about a pin 11 60 mounted in the frame 12 of the apparatus.

When the apparatus becomes operative, that is to say when the strength of current rises so high that the soft iron core 13 is completely attracted by the coil 14, the disk 65 in question will be rotated until a recess 15 provided on the circumference of the disk is brought opposite the roller 9. The unlocking bar 3 will then be forced upward by the pressure exercised by the spring 8. Its upper end will enter the recess 15 and lift out the locking pawl 2, so that the switch will be disengaged, and the circuit broken.

The spindle 11 which is turned owing to the movement of the core 13, drives an auxiliary spindle 20 at a high speed by means of intermediate toothed wheels 16, 17 and 18, 19, or in some other way. This auxiliary spindle, together with the spindle 21 which supports the toothed wheels 17, 18, is mounted in brackets 22 secured to the wall plate of the apparatus. To the said wall plate is secured a hollow cylinder 23, the axis of which coincides with the axis of rotation of the spindle 20. The spindle 20 has, in the 75 interior of the cylinder 23, a part 24 of a larger cross-section; the part 24 is provided with one or more holes 25 extending normally to the spindle 20. In the said holes are guided rods 26, one end of which is bifurcated and carries a roller 27, while the other is screw-threaded and carries a nut 29; and a spring 28 is arranged between the part 24 and the nut, which spring is compressed when the rollers 27 move away from 80 the spindle 20 about which they rotate.

By adjusting the nuts 29 on the rods 26, the spring tension can be regulated in a convenient manner, whereby the centrifugal force acting on the rollers 27 during the 100 rotation of the spindle 20, overcomes the spring tension at a given speed of rotation, so that the rollers 27 are pressed against the inner circumference of the cylinder.

The working of the apparatus is as follows:

When the strength of current exceeds an admissible value, the core 13 or the armature, if desired in opposition to the action of a balance weight or of springs, is attracted by 110 the coils and rotates the spindle 11 and the disk 10 by means of a steel wire 30. This

comparatively slow rotation is transmitted by the toothed wheels 16, 17, 18 and 19 to the spindle 20 which, owing to the speed-multiplying gear, is driven at a high speed. 5 The centrifugal force produced by the rotation, presses the rollers 27, in opposition to the action of the springs 28, against the inner circumference of the cylinder 23 suitably secured to bearings 22, and owing to 10 the friction thus produced, retards the movement, so that the speed of rotation of the disk 10 is reduced. The tension of the springs 28 can be regulated as desired by means of the nuts 29, and in that way also 15 the resistance offered by the retardation device, and consequently also the time elapsing before the disk 10 reaches the end position in which the switch is opened.

When the disk 10 has turned so far that 20 the recess 15 is opposite the unlocking bar 3, the latter will be forced upward into the recess by the spring 8. The unlocking bar after having traveled a short distance, will then strike with a bolt or stop against the 25 locking pawl 2 which will be lifted out, whereupon the switch will be brought into the open position by the action of the weight 4.

An advantage of the switch according to 30 the invention consists in the simplicity of regulation, so that the admissible overload duration can be set exactly for every individual case.

What I claim is:

35 1. An automatic overload switch or cut-out comprising a switch-arm adapted to be released by means of a cam rotated by means of an electromagnetic device operated by the excess of current, a spindle driven at a

high speed by said electromagnetic device, 40 rollers mounted on said spindle and adapted to be forced outward by centrifugal force, a hollow cylinder coaxial with and surrounding said spindle and adapted to be engaged by said rollers, and adjustable 45 springs adapted to restrain the outward movement of the rollers.

2. An automatic overload switch or cut-out comprising a switch-arm, means always tending to move said arm into the open position, a locking bar adapted to hold the arm in the closed position, a cam disk engaged by said locking bar and having a notch adapted to admit the locking bar and thereby to release the switch arm, means for rotating said cam disk automatically when the current reaches a certain maximum, and adjustable means for delaying said rotation. 50

3. An automatic overload switch or cut-out comprising a switch-arm, means always 60 tending to move said arm into the open position, a locking bar adapted to hold the arm in the closed position, a cam disk engaged by said locking bar and having a notch adapted to admit the locking bar and thereby to release the switch-arm, electromagnetic means operated by an excess of current for rotating said cam disk, and an adjustable friction brake adapted to delay the rotation of said disk, and means for adjusting the duration of said delay. 65 70

In testimony whereof I have hereunto set my hand in presence of two subscribing witnesses.

PIETER GERRIT VAN WIJK.
